UNITED STATES PATENT OFFICE.

FRANK M. ASHLEY, OF NEW YORK, N. Y.

ELECTRIC RAILWAY.

SPECIFICATION forming part of Letters Patent No. 677,848, dated July 9, 1901.

Application filed September 13, 1899. Serial No. 730,284. (No model.)

To all whom it may concern:

Be it known that I, FRANK M. ASHLEY, a citizen of the United States, residing at the city of New York, in the borough of Brooklyn 5 and State of New York, have invented certain new and useful Improvements in Electric Railways, of which the following is a full, clear, and exact description.

This invention relates to electric railways 10 of that class in which the working conductors are arranged in a conduit beneath the surface of the roadway.

The invention has special reference to details of construction affecting the insulation 15 of the cable and means for transferring the current therefrom to the motor on the vehicle and to the construction of the conduit at crossings and turnouts, whereby a stable structure is obtained and the collectors are 20 allowed to pass without interruption.

The invention will be described in detail with reference to the accompanying drawings, in which—

Figure 1 represents a longitudinal section 25 of the main conductor and side elevation of the working conductor and return-conductor with other parts in diagram. Figs. 2 and 3 illustrate in section the means for insulating the contact-plungers. Fig. 4 is a perspective 30 view of the current-collector carried by the car. Fig. 5 shows the connection between the car and the current-collector. Fig. 6 is a plan of the conduit at a crossing, the cover-plate being removed. Fig. 7 is a section on 35 line $\alpha\alpha$ of Fig. 6. Figs. 8 and 9 are details of the crossing. Fig. 10 is a plan of a turnout in the conduit. Fig. 11 is a section through the brackets supporting the switch-tongue of the turnout; and Fig. 12 is a plan 40 of the conduit at the turnout, the cover being removed.

The main conductor is indicated by A. It is wound spirally with a rope or cord a of insulating material, and then threaded through 45 a metallic tube B, which is made in sections and joined together by couplings b. The spirals of the cord a are wound in a long pitch, so that the conductor is bare for a large portion of its surface and insulating 50 material is saved. Each of the couplings b is provided on its under side with two downwardly-projecting bosses b', through which

a contact-plunger b² passes vertically. Inside of the boss the plunger is insulated by a bushing b³, which is threaded into the boss 55 at b⁴, and its lower half, which is separated from the upper half, is held in place by the nut b⁵. Inside of the bushing the plunger carries a collar b⁶, which limits the vertical movement thereof. The inner end of the 60 plunger carries a contact-piece b⁷, adapted to be thrust against the bare surface of the conductor A between two of the spirals on the cord a . To exclude moist air from the working parts of the plunger and the main conductor, the boss is surrounded exteriorly by a bulb b⁸, of leather, rubber, or other impervious or flexible material, through which the plunger passes and in which it is sealed in the manner shown in Fig. 3. This bulb is 70 shown as if made of metal, the upper edge being threaded and screwing into a flange surrounding the boss b'. In Fig. 2 the bulb is held in place by a clamp b⁹. The lower ends of the plungers are permanently attached to the sections of a working conductor C, there being one plunger at each end of the section and each section extending from the plunger in one coupling to the first adjacent plunger in the next coupling. Electrical connection between the sections and 75 main conductor is established by lifting the section and causing the plungers to rise into contact with the main conductor. For this purpose the car is equipped with a collector 80 consisting of an arm e, adapted to pass down through the slot in the conduit and carrying a cross-arm e', one end of which is fitted with two contact-rollers e², rigidly mounted, and the other end with two contact-rollers e³, mounted on a spring e⁴. The rollers e² are adapted to make contact with the sections of the working conductor and to lift them to establish 85 connection with the main conductor in the manner hereinbefore mentioned, while the rollers e³ are adapted to make continuous contact with the continuous return-conductor A', and the spring-mounting of them permits them to yield when the plow rises and falls by reason of any irregularities. The plow as 90 a whole is connected with the vehicle through a spring f, which tends to lift it and with it the sections of the working conductor.

With reference to the construction of the

conduit itself in Figs. 6 and 7 I show a crossing wherein the tube containing the main conductor is made to terminate on each side of the crossing; but the opening is bridged 5 by a branch conductor g , extending down one side of the conduit, across the bottom, and up the other side. If desirable, the collecting-wheels e^2 e^3 may be set far enough apart to bridge from one section of the working conductor to the next across the width of the conduit at the crossing, so that there will be no discontinuance of current while the car is passing the crossing. At these points there is always danger of the cover-plates of 10 the conduit being broken by the heavy trucking in the street. This is due to the fact that large sections of the cover overhang the square opening formed by the crossing without support. To furnish the necessary support 15 without interfering with the apparatus, I place a bracket h at each corner of the chamber, directing it diagonally across the square space and terminating it immediately under and against the angle formed in the cover-plate by the crossing slots. This bracket is bolted to the corner of the main conduit at a point where it will not interfere 20 with the other apparatus.

In Figs. 10, 11, and 12 I have illustrated a 25 supporting device for each switch-tongue at a turnout in the conduit similar to the bracket shown in Figs. 8 and 9. In this case the bracket, which is indicated by i , is bolted to the converging side of the walls of the two 30 conduits and extends forward into the angle some distance, where it is fitted with an eye or socket j , in which the end of the switch-tongue s is pivoted. This bracket at the same 35 time serves to support the cover-plates, which at this location in the conduit have to be 40 large in area.

Having described my invention, I claim—

1. In an electric railway a main conductor 45 insulated by a cord or rope wound around it, the spirals of which are arranged at a long pitch to leave bare portions of the conductor between them, in combination with a tube through which the insulated conductor passes, and contact devices passing through the tube 50 to make contact with the bared portions of the conductor, substantially as described.

2. In an electric railway a main conductor 55 insulated by a cord or rope wound around it,

the spirals of which are arranged at a long pitch to leave bare portions of the conductor 60 between them, in combination with a tube through which the insulated conductor passes, said tube being made in sections connected together by couplings provided with openings, a sectional conductor arranged along the 65 side of said tube and carrying plungers passing through the openings in said couplings and adapted to be brought into contact with the bare portions of the main conductor, substantially as described. 70

3. The combination of a tubular coupling b provided with a boss b' , an insulated lining therefor, a plunger passing through the insulated lining and adapted to reciprocate therein, and a flexible diaphragm or bulb secured to the exterior of said boss and to the plunger permitting the latter to reciprocate while excluding the moisture, substantially as described.

4. In an electric railway a collecting device 75 carried by the car, consisting of a rigid arm carrying a rigidly-mounted contact-roller and a flexibly-mounted contact-roller, for the purpose set forth.

5. In an electric railway, the combination 80 of a movable sectional conductor and a fixed continuous conductor forming opposite sides of the circuit, and a collecting device carried by the car, one part of which carries contacts rigidly mounted thereon and adapted to make 85 contact with the sectional conductor and another part of which carries contacts flexibly mounted thereon and adapted to make contact with the fixed conductor of the circuit.

6. In an electric-railway conduit a cover- 90 plate supported at a crossing by means of a bracket secured to the upper part of the converging side of the walls of the conduit.

7. In an electric railway, the combination 95 of two converging conduits, a bracket secured to the converging side walls thereof and extending toward the apex of the angle of the turnout and having a switch-tongue divided at its extremity, substantially as described.

In witness whereof I subscribe my signature 100 in presence of two witnesses.

FRANK M. ASHLEY.
